GLASS TABLE

Maria V. Thornhill, 11705 Longleaf,
Houston, Tex. 77024

Filed Mar. 25, 1970, Ser. No. 22,058

Term of patent 14 years

Int. Cl. D6—03

U.S. Cl. D33—14

FIG. 1

FIG. 2

FIG. 3

FIG. 1 is an oblique view of the glass table constructed in accordance with my design;

FIG. 2 is a side elevational view of the glass table shown in FIG. 1; and

FIG. 3 is a top elevational view of the glass table shown in FIG. 1.

I claim:

The ornamental design for a glass table, substantially as shown.
